UNITED STATES PATENT OFFICE

105,543

DESIGN FOR A TEXTILE FABRIC OR SIMILAR ARTICLE

Jerome Altman, Brooklyn, N. Y.

Application June 4, 1937, Serial No. 69,666

Term of patent 3½ years

To all whom it may concern:

Be it known that I, Jerome Altman, a citizen of the United States, residing in Brooklyn, county of Kings, and State of New York, have invented a new, original, and ornamental Design for a Textile Fabric or Similar Article, of which the following is a specification, reference being had to the accompanying drawing, forming part thereof.

The figure is a plan view of a textile fabric or similar article, showing my new design.

I claim:

The ornamental design for a textile fabric or similar article as shown.

JEROME ALTMAN.
